(57) **CLAIM**

I claim the ornamental design for a paddle portion of a goaltender hockey stick, as shown and described.

DESCRIPTION

FIG. 1 is a perspective view of a paddle portion of a goaltender stick according to the present design;

FIG. 2 is a front side view of the paddle portion of a goaltender stick of FIG. 1;

FIG. 3 is a top plan view of the paddle portion of a goaltender stick of FIG. 1;

FIG. 4 is a bottom view of the paddle portion of a goaltender stick of FIG. 1;

FIG. 5 is a rear side view of the paddle portion of a goaltender stick of FIG. 1;

FIG. 6 is a front elevational view of the paddle portion of a goaltender stock of FIG. 1;

FIG. 7 is a rear elevational view of the paddle portion of a goaltender stick of FIG. 1;

FIG. 8 is a cross-sectional view taken along the line 8—8;

FIG. 9 is a cross-sectional view taken along the line 9—9; and,

FIG. 10 is a cross-sectional view taken along the line 10—10.

The broken lines shown in FIGS. 1-7 form no part of the design and are for illustrative purposes only.
